UNITED STATES PATENT OFFICE.

HANS K. LORENTZEN, OF NEW YORK, N. Y.

DESIGN FOR A FLAG-HOLDER.

54,937.

Specification for Design.

Patented Apr. 20, 1920.

Application filed September 17, 1917. Serial No. 191,872. Term of patent 7 years.

To all whom it may concern:

Be it known that I, HANS K. LORENTZEN, a subject of the King of Denmark, and resident of the borough of Manhattan, in the county of New York, city and State of New York, have invented a certain new, original, and ornamental Design for a Flag-Holder, of which the following is a specification, reference being had to the accompanying drawings, forming part thereof.

In the drawings, Figure 1 is a front view of a flag holder embodying my design; Fig. 2 is an edge view of the same; and Fig. 3 is a top view thereof.

I claim:

The ornamental design for a flag holder as shown.

HANS K. LORENTZEN.
